UNITED STATES PATENT OFFICE.

JAMES A. BISHOP, OF MASCOUTAH, ILLINOIS.

CONTINUOUS-PROCESS COKE-OVEN.

1,166,175.

Specification of Letters Patent. Patented Dec. 28, 1915.

Application filed June 14, 1915. Serial No. 33,968.

To all whom it may concern:

Be it known that I, JAMES A. BISHOP, a citizen of the United States, residing at Mascoutah, in the county of St. Clair and State of Illinois, have invented certain new and useful Improvements in Continuous-Process Coke-Ovens, of which the following is a specification.

The present invention has reference to certain improvements in coke ovens of that general type in which the coking operation is continuous as distinguished from the type in which separate charges of coal are individually coked. The invention has to do, among other things, with the general form of the oven, the manner in which the same is heated, the manner in which the coal is introduced into one portion of the carbonizing chamber, and the manner in which it is removed from another portion thereof.

One of the objects of the present invention is to provide a continuous process oven of such form and construction that the coal can be very rapidly coked, so as to reduce the coking period to a comparatively short time. This will increase the tonnage capacity of a plant of given size as compared to its capacity when operating at a lesser coking rate.

Another object is to provide means for securing a uniform distribution of the coking material throughout the carbonizing chamber, insuring, at the same time, a uniform and regular travel of the material from the point of inlet for the raw material to the point of delivery for the coked product.

Another object of the invention is to provide means for continuously and perfectly cooling the distributing device, so that the same will not be injured or rendered inoperative, by reason of the high temperature existing within the carbonizing chamber.

Other objects and uses of the invention will appear from a detailed description of the same which consists in the features of construction and combinations of parts hereinafter described and claimed.

In the drawings, Figure 1 is a vertical section through a construction of oven embodying the features of the present invention, the discharge port being partially open; it being a section taken on line 1—1 of Fig. 2, looking in the direction of the arrows; Fig. 2 is a horizontal section taken on line 2—2 of Fig. 1, looking in the direction of

the arrows; and Fig. 3 is a horizontal section taken on line 3—3 of Fig. 1, looking in the direction of the arrows.

Referring to the several figures, the particular construction of oven illustrated may be considered as being made up from three divisions broadly numbered 4, 5, and 6, respectively. The division 4 is in the nature of a foundation for the structure, and at the same time it accommodates certain of the operating mechanisms. The division 5 may be termed the heating division, and it is in this division that the heat is generated for heating the carbonizing chamber. The division 6 is the carbonizing division, comprising the carbonizing chamber and the distributing device or mechanism contained therein.

I have thus described the apparatus as sub-divided into three divisions merely for purposes of convenience, and it will be understood that the mechanisms shown in the several divisions may be largely interchanged between the different divisions, or certain of the divisions may even be eliminated entirely. The carbonizing chamber has the floor 7 and the dome-shaped roof 8.

As shown in Figs. 2 and 3, the carbonizing chamber is preferably circular in form, inasmuch as a simple type of distributing device is one which rotates about a vertical axis. The heating division is shown more in detail in Fig. 2. It is provided around its periphery with a number of furnaces or grates 9, wherein are generated the heating gases by means of which the carbonizing chamber is heated effectively for the distillation of the coal.

Leading from the furnaces 9 are heating passages which surround the floor, sides, and roof of the carbonizing chamber, so as to heat the same as uniformly as possible. In the particular arrangement illustrated, there are provided in the heating division a plurality of radial passages 10 and a plurality of radial passages 11, there being as many of each of the passages 10 and 11 as there are furnaces 9. The heating gases from each furnace 9 travel inwardly along the corresponding passage 10, and then turn and travel outwardly along the corresponding passage 11, the passages 10 and 11 being connected together in pairs at their inner ends, as best shown in Fig. 2.

In the roof of the structure, there are a plurality of radial passages 12, or a single

large space 12, depending upon the form of construction adopted, having its outer portion adjacent to the periphery of the carbonizing chamber and having its inner portion communicating with a spent gas flue 13. The outer ends of the passages 12 communicate by means of vertical passages 14 in the peripheral wall of the carbonizing chamber with the outer ends of the passages 11. From the foregoing, it will appear that the heating gases, after having traveled toward and from the center of the structure in the heating device, thereafter travel up and over the carbonizing chamber to the spent gas delivery flue 13. Thus, the arrangement is such that the carbonizing chamber is heated on its bottom, its side walls, and its roof.

The coal is introduced at the central portion of the carbonizing chamber, and is caused to travel toward the periphery thereof, being discharged at a suitable point on the periphery after having remained in the carbonizing chamber the desired interval of time. For this purpose, I have provided the distributing device 14 which is best shown in Figs. 1 and 3. The same comprises a vertical axial member which carries a plurality of radial arms, the radial arms being provided with scrapers or shovels whose function is to cause the carbonizing mass to travel toward the periphery and toward the discharge point.

The coal is delivered into the carbonizing chamber through a central opening or pocket 15. Leading up to this pocket is a tubular passage 16 within which is shown the screw conveyer 17. The conveyer transfers the coal from a hopper 18 to the pocket 15. The distributing device comprises the vertical axial member 19 which carries a plurality of radial distributing arms 20. Each of these arms is provided with shovels 21 set at different radial positions on the arms, so that, as the distributing device rotates, the scrapers will transfer the coal successively farther and farther from the center, and thus eventually deliver it to the point of delivery. To insure this result, the shovels are so placed as to form a spiral, as shown in Fig. 3, instead of being placed on tangents to circles drawn about the center of rotation. When the distributing device rotates in the direction of the arrow of Fig. 3, the desired transfer of material will ensue.

Each of the radial arms is shown as made up from three pipes 22, 23, and 24. The inner ends of these pipes communicate with a central chamber 25, and the outer ends of the pipes of each arm connect into a common member 26. The lower axial portion of the distributing device 19 is hollow, and communicates directly with the chamber 25, said portion 19 serving to deliver a supply

of cooling water to the chamber. From the chamber, this cooling water flows radially outward through the pipes to the members 26. The upper axial portion 27 of the distributing device is also hollow, but does not communicate directly with the chamber 25. On the other hand, corresponding to each of the arms 20 there is a pipe 28 leading from the member 26 up and into communication with the member 27, so that the cooling water will be delivered through the pipes 28 to said member.

Extending upward from the foundation of the structure and through the heating division is a bearing member 29. This bearing member has a flange 30 which is supported by the foundation and serves to transmit thrust from the member 29 to the foundation. The hollow chambered member 25 rests on the upper end of the member 29, which thus provides a bearing on which the distributing device may rotate. A stuffing box 31 between the member 29 and the hollow axial member 19 serves to prevent a downward flow of gas from the carbonizing chamber. Any suitable means may be provided for rotating the member 19 and therewith the distributing device. For this purpose, I have illustrated a worm gear 32 driven by the worm 33. A pipe 34 delivers the cooling water to the axial member 19, a stuffing box 35 providing a water tight connection between these parts.

Leading upwardly from the roof of the carbonizing chamber is the distillate gas delivery pipe 36. This delivers the distillate gases to the pipe 37, from which they may be carried to a by-product recovery apparatus, or to any other point of disposition desired. The upper hollow axial member 27 projects above the pipe 36 and communicates with the cooling water delivery pipe 38. The stuffing boxes 39 and 40 prevent a leakage of cooling water at the point of connection into the pipe 38 and prevent a leakage of gas at the point of exit from the pipe 36, respectively.

At any suitable portion in the periphery of the carbonizing chamber, there is a coke delivery opening 41, best shown in Fig. 1. A downwardly extending chute 42 conveys the coke from this opening into a receiving chamber 43 from whence the coke may be removed through the door 44. By luting in the door 44 so as to close the chamber 43, coke may be collected from an interval of run, and cooled preparatory to removal into the atmosphere. A horizontally traveling door 45 is provided for closing the chute 42. This door has the threaded sleeve 46 working in a bearing 47 within which it may travel horizontally and without rotation. A crank 48 on the threaded rod 49 working with respect to a stationary member 50, serves to force the threaded sleeve 46 back

and forth by reason of the engagement of the threads of the rod with the threads of the sleeve.

If desired, the chute 42 may be water-jacketed, as shown in Fig. 1, the pipe 52 delivering cooling water to the jacket and the pipe 51 removing it therefrom.

In Fig. 3, I have shown the wall of the carbonizing chamber as being provided with a sight hole or opening, through which the operation of the coking process may be observed. The construction illustrated includes a tile 53 extending through the side wall of the carbonizing chamber and carrying at its outer end a cap member 54. This cap member has the outwardly extending neck 55 which is closed by means of a window of mica 56. By looking in through the mica window, the operation of the carbonizing process may be observed, and also the operation of the distributing device. A partition 57 is clamped between the tile and the cap member. This partition has a door seat 58 extending at an angle of approximately 45 degrees to the axis of observation. The observer looking through the window 56 also looks through the seated opening 58 to the interior of the carbonizing chamber. A door 59 may be carried into engagement with the seat so as to close the opening thereof by means of the threaded pin 60 provided with the hand wheel 61. By means of this construction, the door may be closed at all times except when it is desired to make an observation, thus preventing the blackening of the mica window. While I have shown the pin 60 as lying in the same horizontal plane with the axis of observation, still it will be understood that this pin might lie in any other plane desired, and that, as far as this feature of construction is concerned, the main point is that the door 59 travels along an axis lying at an angle to the axis of observation.

While I have herein shown and described only a single embodiment of my invention, still it will be understood that I do not limit myself to the same, except as I may do so in the claims, but that I contemplate within the scope of my invention any equivalent constructions operating in equivalent manners to produce equivalent results.

I claim:

1. In a continuous process coke oven the combination with a carbonizing chamber and means for heating the same, said chamber having a central opening in its floor for the supply of raw material and a peripheral opening for the delivery of coked material, of a rotary element mounted within said chamber, a plurality of radial arms on said element, and shovels mounted on the arms and driven thereby, each shovel being mounted at an angle to the tangent of the circle in which it rotates, and said shovels

being mounted at different radial positions, whereby the coking material is transferred from the center of the floor toward the periphery of the carbonizing chamber.

2. In a continuous process coke oven the combination with a carbonizing chamber, and means for heating the same, said chamber being provided with a central opening in its floor for the supply of raw material and a peripheral opening for the delivery of coked material, of a rotary element mounted in the carbonizing chamber, a plurality of shovels located at different radial positions from the rotary element, each shovel having its effective plane lying at an angle to the tangent of the circle in which it rotates, and driving connections from the rotary element to the shovels, whereby the shovels cooperate with each other to regularly transfer coking material from the central opening of the floor to the peripheral opening during the rotation of the rotary element.

3. In a continuous process coke oven the combination with a carbonizing chamber and means for heating the same, said chamber being provided with a central opening in its floor for the supply of raw material and with a peripheral opening for the delivery of coked material, of a rotary element mounted within the carbonizing chamber, a plurality of shovels within the carbonizing chamber, and operative connections from the rotary element to the shovels for the purpose of driving the shovels in such manner as to secure a transfer of the coking material from the central opening of the floor to the peripheral opening.

4. In a continuous process coke oven the combination with a carbonizing chamber and means for heating the same, there being a central opening in its floor and a peripheral opening in communication with the interior of said chamber, of a rotary element mounted within said chamber, a plurality of shovels within the chamber, each shovel lying at an angle to the tangent of the circle in which it rotates, and operative connections from the rotary element to the shovels for the purpose of driving them, whereby material introduced at one of said openings is transferred by the shovels to the other of said openings.

5. In a continuous process coke oven the combination with a carbonizing chamber and means for heating the same, of a central opening in its floor for the supply of raw material, a peripheral opening for the delivery of coked material, means for continuously feeding raw material to the central opening of the floor, and means for continuously transferring the material so introduced through the carbonizing chamber to the peripheral delivery opening.

6. In a continuous process coke oven the combination with a carbonizing chamber

having a plane floor, and means for heating said chamber, there being a central opening in its floor for the supply of raw material to said chamber and a peripheral opening for the delivery of coked material from said chamber, of means for continuously feeding raw material into the chamber through the central opening of the floor, and means for transferring said material in a relatively thin layer over the floor of the carbonizing chamber to the delivery opening.

7. In a continuous process coke oven the combination with a carbonizing chamber having a plane floor, and means heating said chamber, there being a central pocket in the floor of the carbonizing chamber, and there being an opening for the supply of raw material into said pocket and a peripheral opening for the delivery of coked material from the chamber, of means for continuously supplying raw material into said pocket, and means for continuously transferring the coking material in a comparatively thin layer across the floor of the carbonizing chamber from the pocket to the delivery opening.

8. In a continuous process coke oven the combination with a carbonizing chamber having a substantially plane floor, of heating flues beneath said floor, heating flues in the roof of the carbonizing chamber, connections between the first and second mentioned heating flues, furnaces for the combustion of fuel for the supply of hot gases to the first mentioned flues, there being a central opening in the floor of the carbonizing chamber and a peripheral opening connecting with the interior of the carbonizing chamber, means for supplying raw material to one of said openings, and means for transferring the coking material across the floor of the carbonizing chamber in a relatively thin layer to the delivery opening.

9. In a continuous process coke oven the combination with a circular carbonizing chamber having a substantially plane floor and a dome-shaped roof, and means for heating the floor and roof, there being a central pocket in the floor, and there being a peripheral opening for the delivery of coked material from the carbonizing chamber, of means for supplying raw material into said pocket, a tubular rotary member extending vertically through the pocket and through the carbonizing chamber, the tubular opening thereof being closed at a point within

the carbonizing chamber, a plurality of tubular radial arms mounted upon and driven by said rotary member, tubular braces extending from the outer ends of said arms to the upper portion of the rotary member, and shovels mounted upon and driven by said arms, the tubular openings of the rotary member, arms and braces, being relatively in communication with each other in such manner as to permit the circulation of the cooling medium from the lower portion of the rotary member through the arms and braces to the upper portion of the rotary member.

10. In a continuous process coke oven the combination with a carbonizing chamber having a substantially plane floor and having a dome-shaped roof, and means for heating said floor and roof, there being a central pocket in the floor, and there being a peripheral opening for the delivery of coked material from the carbonizing chamber, of means for supplying raw material to the pocket, a rotary member extending vertically through the central portion of the pocket and carbonizing chamber, a plurality of radial arms connected to and driven by the rotary member, and shovels on said arms, the rotary member and arms being of tubular formation and relatively so interconnected as to permit the circulation of cooling medium through the rotary member and through the arms, and shovels mounted upon and driven by the arms for the purpose of transferring coking material from the central pocket to the peripheral delivery opening.

11. A transferring device for the radial transfer of material across a substantially plane floor, comprising a vertical tubular rotary member having its tubular opening centrally closed, a plurality of tubular arms extending radially from the rotary member at a point beneath said closure, and tubular braces connecting the outer ends of said arms with the rotary member at a point above said central closure, the tubular openings of the rotary member, the radial arms, and the braces, being relatively so connected as to permit the circulation of cooling medium through the rotary member, arms and braces, and transferring shovels on the arms.

JAMES A. BISHOP.
